UNITED STATES PATENT OFFICE.

REUBEN A. MITCHELL AND FRANK A. EMERICK, OF OIL CITY, PENNSYLVANIA,
ASSIGNORS OF ONE-THIRD TO B. B. FREER, OF NEW YORK, N. Y.

FORCED-FEED AND STEAM GENERATOR.

1,331,459.

Specification of Letters Patent. Patented Feb. 17, 1920.

Application filed August 26, 1918. Serial No. 251,498.

To all whom it may concern:

Be it known that we, REUBEN A. MITCHELL and FRANK A. EMERICK, citizens of the United States, residing at Oil City, in the county of Venango and State of Pennsylvania, have invented certain new and useful Improvements in Forced-Feed and Steam Generators; and we do hereby declare the following to be a full, clear, and exact description of the invention, such as will enable others skilled in the art to which it appertains to make and use the same.

The present invention relates generally to an apparatus for the generation of steam, and has particular reference to a combined generator for steam and a forced feed for water employed in the apparatus.

The object is to provide a generator by the use of which steam may be rapidly produced; which includes a forced feed device for the water to insure the circulation of the water through the generator; and to provide an automatic means for insuring the circulation of the water in the apparatus immediately upon application of heat to the generating unit.

Another object is to provide a forced feed and steam generator embodying elements connected in series and with a storage drum or chamber by-passed from the elements to receive steam in excess pressure from the series of elements, the series of elements including devices for maintaining automatically the circulation of water without the employment of external power; and to provide an apparatus of this character which is strictly automatic in action and provided with a pump, the speed of which is proportionate to the volume of steam generated to thus insure the circulation within the apparatus proportionate to the rate of generation of the steam.

With these and further objects in view as will in part hereinafter become apparent and in part be stated, the invention comprises certain novel constructions, combinations and arrangements of parts as subsequently specified and claimed.

In the accompanying drawings,

50 The figure is a longitudinal, vertical section through one form of the apparatus of the present invention, parts being shown in elevation.

Referring to the drawings by numerals, 55 10 designates a furnace body composed of incasing and supporting walls of brick, or

other suitable adaptable material, and which inclose, in the upper end of the furnace, a drum or container 11. The furnace 10 also supports a heating coil 12 adapted to contain water to be vaporized and which is located above the grate of the furnace as shown. A storage or supply tank 13 is arranged in proximity to the furnace 10 and is provided with an inlet 14 through which water may be fed to the tank 13 by a hand pump or other suitable device for introducing water into the system.

Mounted preferably upon the front wall of the tank 13, which also forms a stand-pipe, is a force feed water pump 15 comprising an inclosing casing within which is arranged a pair of vertically disposed cylinders 16 provided in each end and at opposite sides with intake and discharge valves 17 and 18. The intake valves 17 communicate with a chamber 19 formed in the casing 15 between the walls thereof and a partition 20 disposed in the casing, and the chamber 19 has communication with the tank 13 through a pipe 21. The partition 20 also forms an exit compartment or chamber 22 in the casing 15, and into which the outlet valves 18 open. The chamber 22 is connected by a pipe 23 with one end of the heating coil 12 and is adapted to conduct water forced from the pump 15 to the coil 12.

The cylinders 16 of the force feed pump are provided with pistons 24 connected by rods 25 to pistons 26 located in steam cylinders 27 mounted upon the front wall of the tank 13 above the pump 15. Each cylinder 27 is provided with a steam chest 28 which communicates by pipe 29 with the other or outlet end of the coil 12. The piston rods 25 are connected by connecting rods 30 with the cranks of a crank shaft 31 journaled upon the upper end of the tank 13 and provided with a suitable fly-wheel 32. Valve operating links 33 are also connected to the shaft 31 and to the slide valves 34 arranged within the steam chests 28.

The exhaust ports of the steam chests 28 open into a pipe 35 which leads to the top of the drum 11 and returns the steam and water of condensation to the drum, the water and steam being separated in the drum. The lower end of the drum 11 is connected by a return pipe 36 to the stand-pipe 13 for returning water from the drum 11 to the stand-pipe or tank.

The pressure of steam from the serial

coil 12 is regulated by an adjustable pressure regulator or reducing valve 37, and excess steam pressure at the outlet end of the serial coil 12 is relieved through a by-pass 5 pipe 38 leading from the coil 12 to the top of the drum 11, and including an adjustable automatic pressure regulator 39.

The high pressure in the coil 12, regulated by the tension on the regulator or governor 10 39, makes a differential pressure between the coil 12 and the drum 11 of about fifteen to twenty pounds and sufficient to operate the engine which drives the water pumps.

As soon as heat is applied to the coil 12 15 the water expands through the pipe 29 and into the cylinders 27 for operating the pistons 26 and the water pump 15. As steam is generated it also follows the same course and is maintained under a predetermined pressure 20 in the coil 12 by the regulator 37, the regulator 39 being actuated upon excess of a predetermined pressure to admit the steam to the top of the drum 11. The operation of the pistons 26 forces water from the stand-pipe 25 35 through the feed pipe 23 into the coil 12. The water is converted into steam, passes through the cylinders 26 in the operation of the steam engine, and is finally delivered into the pipe 35 which conducts the 30 steam and water of condensation to the top of the drum. The water circuit through the drum is completed by the return pipe 14 which is arranged between the bottom of the drum and the lower end of the stand-pipe. 35 The drum 11 is provided with an outlet pipe 40 by means of which steam may be taken from the drum for any suitable purpose, such as for driving engines, for use in steam heating systems, and the like.

40 What is claimed is:

1. In a forced feed and steam generator, the combination of a heating coil, a boiler connected to one end of the coil to receive steam therefrom, a water feed means connected to the other end of the coil, and including steam-actuated devices, connections between the first end of the coil and the steam-actuated devices to operate the latter, and regulating means controlling the passage of steam from the coil to the steam-actuated devices and the boiler.

2. In a forced feed and steam generator, the combination of a heating coil, a boiler, a reduction valve for maintaining reduced pressure in the boiler, a water feed device, steam-actuated means for operating the water feed device and including connections with the coil for receiving steam therefrom, a connection between the steam-actuated 55 means and the boiler for delivering exhaust steam to the latter, and means for carrying off the products of condensation from the boiler to the water feed means.

3. In a forced feed and steam generator,

the combination of a heating element, a boiler, forced feed means for water connected to one end of the heating element, steam-actuated means connected to the heating element for operating the forced feed means for the water, means for delivering 65 exhaust steam from the steam-actuated means to the boiler, a return connection between the boiler and the forced feed means for returning water of condensation thereto, and a reduction valve between the heating 70 element and the boiler for providing a differential pressure for operating said steam-actuated means.

4. In a forced feed and steam generator, the combination of a heating element, a boiler, a forced feed means for water connected to the heating element, steam-actuated devices for the forced feed means and connected to the heating element for operation by steam generated therein, and a pressure reduction valve connecting the heating element to the boiler for providing a differential pressure between the two for actuating the steam-actuated devices, and a second pressure controlled valve between the heating 85 element and the steam-actuated devices.

5. In a forced feed and steam generator, the combination of a heating element, a boiler connected to the heating element, a forced feed water device connected to the heating element and having steam-actuated devices for operating the same, a pressure controlled connection between the heating element and the steam-actuated devices for operating the same by steam generated in the 95 heating element, a reduction valve between the heating element and the boiler for causing a differential pressure between the two for actuating said steam-actuated devices, an exhaust pipe between said steam-actuated 100 devices and the boiler for collecting exhaust steam in the latter, and a drain pipe between the boiler and the forced feed water means for returning water of condensation thereto.

6. In a forced feed and steam generator, the combination of steam-actuated forced feed means for water, a heating coil connected to said water feeding means, a boiler connected to the heating coil to receive steam therefrom, a direct connection between the 110 coil and the steam-actuated water feeding means, and a second connection between the coil and the boiler and including a pressure reduction valve for causing a differential 115 pressure between the two for actuating said steam-actuated water feeding means.

In testimony whereof we affix our signatures in presence of two witnesses.
